Des. 220,257
Patented Mar. 23, 1971

220,257

PARTITION SPACER

Jerome Philip Schooler, Roslyn Heights, N.Y.
(10 Seymour Place, London W.1, England)

Filed Nov. 14, 1969, Ser. No. 20,090

Term of patent 14 years

Int. Cl. D25—01

U.S. Cl. D13—6

FIG. 1 is a top perspective view of a partition spacer embodying my design;

FIG. 2 is an end elevation view of the partition spacer of FIG. 1;

FIG. 3 is a side elevation view of the partition spacer of FIG. 1; and

FIG. 4 is a bottom plan view of the partition spacer of FIG. 1.

I claim:

The ornamental design for a partition spacer, substantially as shown.
